UNITED STATES PATENT OFFICE

HAROLD L. TOWER, OF GREENVILLE, MICHIGAN

INTERNAL-COMBUSTION ENGINE

Application filed July 18, 1928. Serial No. 293,667.

This invention relates to internal combustion engines, and aims to provide a novel and improved motive power of this character having cylinders and pistons for providing explosion and compression chambers, the principle of which may be used in connection with both two and four cycle engines for materially increasing the efficiency thereof.

Another object of the invention is the provision of a crank case having partitions therein for providing separate air-tight compartments for the cylinders in which air is compressed and supplied to the explosion chambers.

15 A further object of the invention is to provide an engine having compound cylinders and pistons of stepped construction, the upper portions of which are used as explosion chambers, while the lower portions are used 20 as air compressors to provide a super-charged engine.

A still further object of the invention is the provision of manifolds in connection with a carburetor to receive compressed air from 25 the compression chambers of the crank case and cylinders and conduct the same to the carburetor for vaporizing the liquid fuel and for conveying the mixture to the explosion chambers, the entrance to which latter is controlled by the usual cam shaft and poppet 30 valve structure.

It is also an object of the invention to provide an engine of the above indicated character, which is substantial in construction, 35 which may be manufactured rather economically, and one which will be thoroughly efficient and practical in use.

With the foregoing and other objects in 40 view, which will be apparent as the description proceeds, the invention resides in the construction and arrangement of parts, as hereinafter described and claimed, it being understood that changes can be made within the 45 scope of what is claimed, without departing from the spirit of the invention.

The invention is illustrated in the accompanying drawings, wherein:

Figure 1 is a side elevation of my improved engine,

50 Figure 2 is a vertical cross section through

one of the cylinders taken on line 2—2 of Figure 1, and

Figure 3 is a longitudinal vertical section taken on line 3—3 of Figure 2.

In carrying out my invention the cylinders 10 of the engine are of stepped construction each provided with a bore 11 at the upper portion and a bore 12 of larger size at the lower portion, said cylinders being of the double-wall water-cooled type closed at their 15 upper ends by heads 13 and comprising annular walls 14 at the upper ends of the larger bores 12. A piston 15 also of stepped construction works within the bores of the cylinders, the main or body portion 16 being adapted to reciprocate in the bore 12 while a skirt 17 at the lower end of said main portion reciprocates in the bore 13, being provided with the usual packing rings 18 and 19 respectively. 20

Connected to the pistons 15 on the wrist pins 20 are connecting rods 21 from a crank shaft 23 enclosed within a crank case 22 formed in two longitudinal sections 25 and 27, the upper section being formed integral with the cylinders and the lower section connected thereto in the usual manner by bolts passing through the meeting flanges, as shown in Fig. 2. The crank case is divided into separate compression chambers below the cylinders by vertical walls 25' and 26 between which the bearings 24 for the crank shaft are formed, and on one end of the crank shaft 23 is mounted a flywheel 28, while on the opposite end thereof is a pulley 29 about which is trained a chain or belt 30 extending upwardly to and around a pulley 31 on the end of a cam shaft 32 supported above the cylinders by suitable bearings 33, said shaft carrying a plurality of cams 34 for operating poppet valves 35 at the ends of passageways 36 leading into the upper ends of the cylinders, said valves being opened downward by the cams and moved to closed position against the seats 40 by coil springs 39 encircling the stems 38. 30

At one side of the crank case 22 and for each compartment therein is a nipple 41 provided at its outer end with a valve seat 43 for a valve 44 the outwardly projecting stem 45

of which is slidable in a bearing 46 formed on the nipple, said valves being actuated to closed position by a coil spring 47 interposed between the bearing and a head 48 at the outer end of the stem. These valves are 5 adapted to supply air to the compression chambers formed in the crank case below the several cylinders, the operation of the pistons causing suction in the compression chambers which will open the valves for a supply 10 of air on the up-stroke of the pistons to compress it on the down-stroke at which time said valves will be automatically closed by the springs. Correspondingly at the opposite side of the crank case are tubular extensions 49 having seats 50 for outlet valves 51 the stems 52 of which are slidable in bearings 53, said valves being normally closed by springs 54 interposed between said bearings and heads 55 at the outer ends of the 20 valve stems, and the operation of these valves is such that when the pistons are on their downward movement they will be forced open due to compression of air in the crank case so as to permit the compressed air to pass by the valves, but when the pistons are on their upward strokes the valves are closed by the springs 54, thus the valves 44 permit the feeding of air into the crank case upon upward movement of the pistons and valves 51 allow the compressed air to pass from the crank case upon downward movement of the pistons into branch pipes 56 of a manifold 57-58 communicating with a passageway 35 35 59 leading into the lower portion of a carburetor 60.

Located in the annular walls 14 of the cylinders at one side of the latter are valves 61 closing against seats 62 and having outwardly projecting stems 63 slidable in bearings 64 formed integrally on the outside of the cylinders with coiled springs 65 encircling the stems and interposed between said bearings and heads 66 on the stems so as to 40 normally close the valves. It can be seen that when the pistons move in a downward direction valves 61 will open due to suction in the lower portions 12 of the cylinders around the body portion of said pistons, and 45 that when the pistons move in an upward direction the valves will be closed by the coil springs 65, providing for a compression of air in this part of each cylinder. For conducting this compressed air to the manifold 55 57-58 leading to the carburetor a valved outlet 67-75 is formed at the opposite side of each cylinder, the valve seat 69 receiving a valve 70 opening outward with respect to the compression chamber and the valve stem 60 71 slidable in a suitable bearing 72 being actuated to closed position by spring 73 between said bearing and head 74 at the outer end of the stem. About the stems 71 are arranged coil springs 73 which engage the 65 bearings 72 and heads 74 on the stems so as

to normally hold the valves in closed position. It can be seen that when the pistons move in an upward direction these valves will be forced open due to the compressing of air in the portions 12 of the cylinders, and that when said pistons move in a downward direction the valves will be closed by the coil springs 73, the compressed air being conducted to the manifold 57-58 by pipes 77, as hereinbefore mentioned.

The carburetor 60 is of that type in which the compressed air from the manifold 57 may pass around the needle valve 78 thereof to cause liquid fuel fed to the carburetor by pipe 79 to mix and be vaporized by the compressed air. Attached to the upper end of the carburetor, as at 80, is a manifold 81 which has a horizontal pipe 82 with upturned ends 83 communicating with horizontal branch pipes 84 intermediate their ends. At opposite ends of the branch pipes 84 are inwardly and downwardly extending pipes 85 leading to the cylinder heads, as at 86, to connect with the passageways 36 in said heads for supplying the cylinders with the fuel mixture. By referring to Figure 2 of the drawings, it can be seen that the stems 38 of the poppet valves 35 at the inlet passageways 36 slide through suitable bearings 87 in the portions 85 of the manifold 81, and that exhaust pipes 88 extend from the passageways 36 (Fig. 3) for exhausting the cylinders by way of the poppet valves at the lower end of said passageways, the stems of the valves sliding through the manifolds 88 in a similar manner to that already described with reference to the valve stems 38 which pass through the manifold 81. In operation of the invention, the pistons 15 reciprocate in the cylinders 10, the upper or body portions 16 working in the bore portion 11 while the skirts 17 work in the bores 12. On the downward strokes of the pistons, the valves 61 in the upper ends of the annular compression chambers 12 are opened by suction to permit air to enter therein, and the valves 51 also opened by suction to permit air compressed in the crank case to pass to the branch portions 56 of the manifold 57. Upon upward strokes of the pistons, the above mentioned valves are closed by the springs and the valves 70 in the compression chambers of the cylinders are opened to allow the compressed air to pass into the branch pipes 77 of the manifold 75, during which operation the valves 42 are opened by suction for supplying air to the crank case to be compressed upon the next downward stroke of the pistons. The air forced from the compression chamber of the cylinder and crank case passes upwardly to the manifold 57-58 and then to the carburetor where the liquid fuel is mixed and vaporized with the compressed air and passes through the manifold 81 to the upper end of the explosion chambers in the cylinders for compression and explosion therein.

As the pistons reciprocate in the cylinders the crank shaft and cam shaft are rotated to control the opening and closing of the poppet valves to the explosion chambers so that the fuel mixture may enter the explosion chambers and exhaust gases pass therefrom.

It can be seen that an engine as above described may be constructed so as to be used as a two-cycle or a four-cycle engine, as the principle of the engine is such that the air is compressed prior to the entrance thereof to the explosion chambers.

Having thus described my invention, what I claim as new is:

15 1. An internal combustion engine comprising a plurality of cylinders each having bores therein of different diameters, the bore at the upper end of the cylinder being of less diameter than the bore at the lower end 20 thereof, pistons in said cylinders each having portions of different diameter working in the aforesaid bores, the smaller bore forming an explosion chamber and the annular space around the piston in the larger bore 25 forming a compression chamber, valves at the upper end of the annular bore, one admitting air upon downward movement of the piston and the other providing an outlet for the compressed air upon upward movement of 30 the piston, and a manifold connected to the outlet valve, the pistons being connected to a crank shaft; together with a crank case having partitions forming compression chambers below the pistons respectively and having 35 valved inlet and outlet openings, pipes connecting the outlet openings to the aforesaid manifold, a carburetor connected to said manifold at one side thereof, and a manifold connected to the carburetor at the other side 40 thereof and to the explosion chambers of the engine cylinders.

2. An internal combustion engine comprising an plurality of cylinders, each having an explosion chamber and a compression chamber, pistons slidale in said cylinders for compressing air in the compression chambers and for operation in the explosion chambers, valves for controlling the inlet of air into the compression chambers and the outlet of 45 air from said compression chambers, a manifold in communication with the outlet valves, an enclosed crank case, a crank shaft mounted in said crank case and connected to the pistons, valves in said crank case for admitting air thereto upon upward movement of the pistons and providing an outlet for the compressed air upon downward movement of the pistons, the aforesaid manifold also communicating with the outlet valves 50 from the crank case and with the explosion chambers for supplying compressed air from the compression chambers and crank case to the explosion chambers, said crank case being divided into air-tight compartments one 55 arranged below each of said cylinders, and

a carburetor in the manifold for supplying fuel to the compressed air passing from the compression chambers and crank case to the explosion chambers.

3. An internal combustion engine comprising a plurality of cylinders, each having an explosion chamber and a compression chamber, pistons slidale in said cylinders for compressing air in the compression chambers and the fuel mixture in the explosion chambers, valves for controlling the inlet and outlet of air to and from said compression chambers, a manifold in communication with the outlet from the compression chambers, a crank case, a crank shaft mounted in said crank case and connected to the pistons, valves in said crank case for admitting air thereto upon upward movement of the pistons and for providing an outlet of compressed air upon downward movement of the pistons, said manifold also communicating with the outlet valves from the crank case and in communication with the explosion chambers for supplying compressed air from the compression chambers and crank case to the explosion chambers, said crank case being divided into air-tight compartments one below each of said cylinders, a carburetor arranged in the manifold for supplying liquid fuel to the compressed air passing from the compression chambers and crank case to the explosion chambers, and valves for controlling the passage of the fuel mixture into the explosion chambers.
